UNITED STATES PATENT OFFICE.

CHARLES E. POPE, OF SOUTH HADLEY, MASSACHUSETTS, ASSIGNOR TO
UNIVERSAL TOBACCO HOISTING COMPANY OF HOLYOKE, MASSACHU-
SETTS, A FIRM.

TOBACCO-HOISTING APPARATUS.

SPECIFICATION forming part of Letters Patent No. 759,190, dated May 3, 1904.

Application filed September 22, 1903. Serial No. 174,189. (No model.)

To all whom it may concern:

Be it known that I, CHARLES E. POPE, a citizen of the United States of America, and a resident of South Hadley, in the county of Hampshire and State of Massachusetts, have invented certain new and useful Improvements in Tobacco-Hoisting Apparatus, of which the following is a full, clear, and exact description.

This invention relates to an improved apparatus for hoisting tobacco, the pluralities of the bunches or "hands" of which are engaged over a lath or bar, strip or rod, so that the tobacco may with facility be carried from the floor of the shed upwardly as high as required, to be taken and stowed away at any of the variably-elevated "bents" or lofts in the shed.

The object of the invention is to provide an apparatus for the indicated purpose, which is simple and inexpensive of construction, most easy and convenient in operation, and incapable of becoming deranged after protracted use; and the invention consists in the combinations or arrangements of parts and the construction of parts, all substantially as hereinafter described, and set forth in the claims.

Reference is to be had to the accompanying drawings, in which the improved tobacco-hoisting apparatus is fully and clearly illustrated, and in which—

Figure 1 is a front elevation of the same, the lower portions of the carrier-chains being omitted. Fig. 2 is a sectional elevation as seen on the line 2 2, Fig. 1. Fig. 3 is a perspective representation of a preferred construction of combined chain and lath-supporting hook. Fig. 4 is a perspective view of a modified form of chain-link and hook, which is capable of advantageous utilization.

Similar characters of reference indicate corresponding parts in all of the views.

In the drawings, A represents the main supporting body or frame of the device, adapted to be sustained at a high location in the tobacco-shed—as, for instance, by being by means of the opposite upstanding hooks a a, suspended from an overhead beam or bar to be found or provided in the shed.

The shaft B, which is journaled through the

ear-lugs b b of the said frame or body, has affixed thereon in opposition and suitably distanced the pair of sprocket-wheels C C and also affixed thereon a ratchet-wheel D, with which engages a pawl d, pivotally hung within ear-lugs f f of the main frame. 50 55

F F represent a pair of flexible carriers, advantageously constituted by sprocket-chains, which have running engagements with and around the said pair of sprocket-wheels and dependent therebelow, and at intervals the chains are provided with forwardly-projecting hooks g g, those of one chain being arranged opposite and at the same level with those of the other chain, said hooks readily receiving engagement therewithin, and for the support of the same the laths or straight strips x, on which the hands of the leaf-tobacco are carried. 60 65

As shown in Fig. 3, the chain-links, which are produced from sheet metal struck up and having bar members at an end of each link engaged in an eye of the relatively next link, have integral extensions bent to form the hook g. 70

In Fig. 4 the hook member is separately formed from sheet metal having opposite lips g' g'', which embrace the vertical opposite members of the link, these two different hook formations being illustrated to show that it is not my purpose to limit the invention to any specific hook and link construction. 75 80

The apparatus being mounted in place in the tobacco-shed a person on the floor places the laths carrying the hands of tobacco on one of the lower pair of hooks and by drawing 85 downwardly on the rear course of the chain the front course is elevated, carrying the tobacco therewith, the laths with the tobacco being taken off at any of the bents desired. The pawl engaging the ratchet-wheel prevents 90 any falling back of the front course of the chain, and the tobacco being elevated thereby even should the person momentarily discontinue the elevating action and leave the chain subject to the weight of the tobacco-carrying 95 laths thereon.

The apparatus is also available with great convenience for the taking down of the to-

bacco, in which case the laths are placed on upper pairs of the hooks and the pawl is swung upwardly and left out of engagement with the ratchet-wheel, so that the weight of the tobacco will cause the front course of the chain to descend, or if such weight is insufficient to overcome the friction in the parts the chains may be hauled by hand in the proper direction.

10 Having thus described my invention, what I claim, and desire to secure by Letters Patent, is—

15 1. In a tobacco-hoisting apparatus, the combination with an elevated support having a shaft journaled thereon provided with opposite sprocket-wheels, and having a ratchet-wheel, of a pair of sprocket-chains in running engagement around and depending below said wheels, and provided at intervals with oppo-

sitely-arranged lath-holding hooks, and a pawl 20 engaging said ratchet-wheel.

2. In a tobacco-hoisting apparatus, the combination with an elevated support having a pair of opposite upwardly-extending hooks, and having a shaft journaled thereon which is 25 provided with oppositely-arranged sprocket-wheels, of a pair of sprocket-chains in running engagement around, and depending below said wheels, which are provided at intervals in the lengths of the chains with oppositely-disposed lath-holding hooks.

Signed by me in presence of two subscribing witnesses.

CHARLES E. POPE.
